(57) **CLAIM**

The ornamental design for a multi-compartment container, as shown and described.

DESCRIPTION

FIG. 1 is a front perspective view of a multi-compartment container showing, in particular, the ornamental design thereof;

FIG. 2 is a top plan view of the multi-compartment container of FIG. 1;

FIG. 3 is a front end view of the multi-compartment container of FIG. 1. It will be understood that a rear end view will be a mirror image of the front end view; and,

FIG. 4 is a left side elevation view of the multi-compartment container of FIG. 1. It will be understood that a right side elevation view will be a mirror image of the left side elevation view.

The appearance of the underside of the invention is not claimed and is therefore not disclosed in the drawing views.
